UNITED STATES PATENT OFFICE

FREDERICK G. SHULL, OF NEW HAVEN, CONNECTICUT

TOBACCO PIPE

Application filed December 18, 1928. Serial No. 326,870.

The present invention relates to tobacco pipes, and more particularly to pipes of this character having a trap or equivalent chamber formed in the stem.

5 The purpose and object of the present invention is to provide a pipe of this character which shall combine a trapping chamber designed to collect liquid present in the bore of the stem, and prevent the flow of such 10 liquid to the mouthpiece, in conjunction with a removable stem portion which may be easily and tightly inserted within the trapping chamber.

With this and other objects in view, the 15 several features of the invention consist in certain novel features of construction, combinations and arrangements of parts, herein-after described and claimed, the advantages of which will be obvious to those skilled in 20 the art from the following description.

The accompanying drawing illustrates a tobacco pipe, embodying the improved features of the invention, shown in longitudinal section.

25 As indicated more particularly in the drawing, the pipe comprises generally a bowl portion 14 having the usual chamber 16 formed therein and communicating with a bore 18 formed in an integral stem 20. Connected 30 with the stem 20 is a condensing chamber and trap 22 which comprises essentially a thin metallic sleeve 24 having a reduced threaded end 26 adapted to be received in an internally threaded portion 28 formed in the end of 35 the stem portion 20. The reduced threaded end 26 is provided with a bore 30 registering with the bore 18 and affording free communication between the interior 16 of the bowl and the chamber 22. The sleeve 24 forming 40 the chamber 22 is conveniently surrounded with a coat 32 of rubber or similar material having the approximate diameter of the stem 20, and presenting a smooth, continuous surface with relation thereto. The end portion 45 of the stem carrying the mouthpiece is preferably and conveniently separable from the sleeve 24 to permit detachment and insertion of this portion of the stem. To this end the stem comprises a portion 34 of rubber or 50 equivalent material having the usual bite 36

formed at the end and a reduced portion 38 normally received loosely within the metallic sleeve 24 until the shoulder 40 upon the portion 34 abuts against the end of the sleeve in the manner shown. It is practically impossible in a construction of this character to provide a fit between the hard-rubber stem 34 and the metallic sleeve 24 of such a character that a tight seal would be obtained. I have overcome this disadvantage through the provision of a stem adjustment, comprising essentially an elongated metal thimble 42 having a portion 44 threaded within the stem 34, and an enlarged end to provide a shoulder 46 abutting against the end of the stem, the thimble having a bore 48 which registers with the bore in the stem, and affords free communication between the end of the stem and the chamber 22. By virtue of this adjusting thimble, I am enabled to vary the diameter of the reduced portion of the stem 34 sufficiently to permit a tight fit in each individual case between the stem and the metallic sleeve 24. This may be conveniently accomplished by heating the stem, as for example, by dipping the stem in hot water sufficiently to soften the material slightly. Thereafter, by adjusting the thimble through the provision of the slot 48, a greater or less compression can be exerted upon the reduced portion of 55 the stem, and the diameter correspondingly varied to the slight extent necessary for a tight fit. With this construction the necessary sealing fit between the stem and the condensate chamber is secured, and a satisfactory 60 construction results.

70 What is claimed is:

1. A tobacco pipe comprising a bowl portion having a hollow stem extending therefrom, a separable stem portion having an integral reduced connecting end, and means extending within the reduced end and adapted to modify the diameter thereof to insure a tight fit. 75
2. A tobacco pipe comprising a bowl portion having a hollow stem extending therefrom, a separable stem portion having an integral connecting end, a metallic sleeve interposed between the two stem portions to provide a trapping chamber, and means for 80
3. A tobacco pipe comprising a bowl portion having a hollow stem extending therefrom, a separable stem portion having an integral connecting end, a metallic sleeve interposed between the two stem portions to provide a trapping chamber, and means for 85
4. A tobacco pipe comprising a bowl portion having a hollow stem extending therefrom, a separable stem portion having an integral connecting end, a metallic sleeve interposed between the two stem portions to provide a trapping chamber, and means for 90
5. A tobacco pipe comprising a bowl portion having a hollow stem extending therefrom, a separable stem portion having an integral connecting end, a metallic sleeve interposed between the two stem portions to provide a trapping chamber, and means for 95
6. A tobacco pipe comprising a bowl portion having a hollow stem extending therefrom, a separable stem portion having an integral connecting end, a metallic sleeve interposed between the two stem portions to provide a trapping chamber, and means for 100

modifying the size of the integral connecting end of the separable stem portion to insure a tight fit with the metallic sleeve.

3. A tobacco pipe comprising a bowl having a hollow stem extending therefrom, a metallic sleeve having a reduced neck portion threaded in the stem and provided with an outer coat of rubber or equivalent material having approximately the diameter of the stem portion, and a detachable stem portion having an integral reduced end designed to be received within the metallic sleeve with a press fit.

4. A tobacco pipe comprising a detachable stem having an integral reduced end, an adjusting member received within the end of the stem and adjustable lengthwise thereof, the adjusting member having a shoulder abutting against the reduced end of the stem to modify the diameter thereof.

5. A tobacco pipe comprising a detachable stem portion having a bore extending therethrough, and an integral reduced neck at the connecting end, internal threads formed within the stem portion surrounding the bore substantially beyond the reduced neck, and a hollow plug threaded within the stem and having a shoulder abutting against the end of the reduced neck to modify the diameter of the reduced neck exerted longitudinally of the stem.
